PLUG TYPE VALVE

Elliott E. Moody, Cranford, N. J.

Application January 8, 1953, Serial No. 330,315

8 Claims. (Cl. 137—315)

This application is a continuation-in-part of the application of Elliott E. Moody for Improved Plug Type Valve, Serial No. 291,610, filed June 4, 1952, now abandoned.

This invention relates to valves and is particularly concerned with that type known as plug valves. Plug valves are preferred in particular situations because of their inherent structural characteristics. However, they have one disadvantage, namely, the difficulty of opening and closing the valve due to the large frictional resistance between the valve and the valve seating surface.

Accordingly, there have been developed two types of plug valves; one known as a lubricated plug valve in which the valve surfaces are lubricated by special means, and the other known as the nonlubricated type in which the valve is raised from its seat before it is rotated. This invention is concerned solely with the nonlubricated type of plug valve.

To open a nonlubricated plug valve of the type known to the prior art, it is customary to provide means for first lifting the valve slightly, thus freeing it from its seat, after which it may be turned readily from closed to open position. After being turned to open position, the valve is customarily returned to seated position to prevent vibration that might be set up by the passing fluid should the valve remain suspended from the valve stem and be unsupported at its lower end. To close the valves of the prior art, the reverse procedure is followed. That is, the valve is first raised from its seated position, then turned from open to closed position, and then reseated in closed position. In other words, prior art practices contemplate raising and lowering the valve in each changed position. This is time consuming and in general has been considered objectionable. Various means have been heretofore provided for lifting the valve from seated position so as to make it possible to turn the valve easily from closed to open position or vice versa. The problem of repacking the stuffing box while the valve is in use has also been considered. In some constructions using a single stuffing box, the repacking can be done while the valve is in seated position, either open or closed. In other constructions using an upper valve seat, repacking can be done only while the valve is open and in engagement with the upper seat. In this latter construction, however, two stuffing boxes have been required.

According to the present invention as disclosed herein, it is proposed to overcome the deficiencies of the prior constructions by providing a valve in which to shift the valve from closed to open it is merely necessary to raise the valve from seated position to a maximum up position. The lifting of the valve from full down seated position to maximum up position is achieved by unidirectional rotation of a hand wheel related to the valve stem. That is to say, the operator to open the valve merely turns the hand wheel to the left as far as it will go with the opening of the valve occurring automatically. To close the valve the operator merely reverses the procedure.

Accordingly, one of the objects of the present invention is the provision of automatically operating means for causing the valve to turn from closed to open position as it is being raised and from open to closed position as it is being lowered.

The valve when in up position, while entirely free

of the main valve seats, will be supported at its lower end against vibration and will have a secondary circular seat preferably conical in shape at its upper part in engagement with a corresponding valve seat 5 at the lower end of the opening in the cap or bonnet through which the valve stem extends. In this way, the valve will be fully supported at the top and bottom and any leakage past the valve stem, while the valve is in open position, will be completely eliminated.

The construction of the present invention makes it possible for the stuffing box of the valve stem to be repacked at any time whether the valve be closed or open. If the valve is closed, no fluid under pressure will be present at the valve stem, and if the valve is open that fluid under pressure that surrounds the plug valve will be prevented from escaping upwardly along the valve stem by virtue of the engagement of the secondary valve surface on the upper part of the plug valve with a corresponding valve seat on the bonnet. Thus, repacking operations can be conducted at any valve setting.

The foregoing objects of the invention may be more particularly understood by reference to the accompanying drawings in which:

Fig. 1 is a vertical section of the valve showing the construction for causing automatic opening of the valve, the valve being shown in closed position.

Fig. 2 is a vertical section of the valve shown in open position.

Fig. 3 is a sectional plan view taken on the line 3—3 of Fig. 1.

Fig. 4 shows an alternative form of spring mechanism for causing automatic opening of the valve.

Referring now to the drawings, it will be observed that the valve comprises a casing 2 adapted to be connected to a piping system in the usual way, it being understood that the particular type of connection with a piping system may be by other means than the screw threads 4 shown in Fig. 3. The method of connection of the valve to the pipes has no bearing on the invention.

The casing 2 includes separately inserted main valve seats 6 which are shaped to coincide with the corresponding seating surfaces of a conical plug valve 8. The seats 6 may be integral with the casing or their faces may be flush with the interior surface if such construction is found more convenient.

The plug valve 8 in the form of a truncated cone has a passageway 10 extending therethrough. When the valve is in closed position, the passageway will be as in Fig. 1 and when the valve is open as in Fig. 2, the passageway obviously cooperates with the port opening 12 which extends the length of the valve body. 55 When the valve is in closed position, as shown in Fig. 1, with passageway 10 at right angles to the port opening 12, the plug valve seating surface 14, which comprises the outer surfaces of the plug valve that are disposed between the ends of the passageway 10, is in intimate contact with the seats 6 and the flow of fluid through the valve is thus effectively stopped. Because of the tight engagement of the plug valve with the seats 6, it will be seen that when the valve is closed, no fluid may flow into the area 16 surrounding the plug valve.

The plug valve 8 is constructed to act integrally with an outer hollow stem 18 to which is fastened a handle or other suitable device 20 designed to provide auxiliary means if needed for imparting rotary motion to the stem 18 and the attached valve 8. The extent of the rotary motion of handle 20 is limited to 90° and stops 22 and 23 (see Fig. 3) are provided at suitable positions so that the valve will be completely closed when the handle is against stop 23 and completely open when against stop 22.

The plug valve 8 is also provided with a threaded portion 26 at the lower interior of outer stem 18, the threads of which engage with corresponding threads 24 on the lower end of an inner stem 28. This threaded relationship between stems 18 and 28 is for the purpose of moving the plug valve up and down with respect to the main valve

seats 6 and an upper valve seat 30 located in the valve cap or bonnet 36. Seat 30 is concentric with the vertical axis of the valve and surrounds the lower end of outer stem 18. The plug valve 8 is also provided with an upper seating surface 32 which is so shaped as to make intimate tight contact with the upper valve seat 30 when the valve is in uppermost position. The purpose of bringing upper seating surface 32 into engagement with the upper valve seat 30 is two-fold, namely, (1) to lock the plug valve in position against rotation when it is in other than fully closed position, and (2) to provide a tight seal against leakage from the area 16 outwardly about outer stem 18 to a stuffing box 34. By providing the tight seal between valve seat 30 and the upper seating surface 32 when the valve is in uppermost position, the stuffing box may be repacked while fluid under pressure is maintained within the valve in area 16.

The valve bonnet or cap 36 is securely attached to the top of the valve casing by means of tap bolts 38. The casing and cap together form a valve body. A tight fit at 40 exists between the casing and cap so that no fluid can escape. Other means of securing the cap to the casing could, of course, be used but such variation would in no way affect the invention herein disclosed.

Extending upwardly from cap 36 is a vertical tubular portion 42 which contains the stuffing box and through which pass the outer and inner stems. Also extending upwardly from the cap 36 is a yoke 44 which is shown most clearly in Fig. 3. At the top of the yoke is a yoke collar 46 shown in section in Figs. 1 and 2. This collar has a recessed portion 48 which is dimensioned and proportioned to receive and act as a housing for a collar 50 which is affixed to inner stem 28. A companion flange 52 is securely attached to the yoke collar by means of tap bolts 54 or by any other suitable means. The companion flange is correspondingly recessed and proportioned to fit about the upper portion of the collar 50 with adequate clearances to permit rotary motion of the collar within the recess in the yoke collar.

A hand wheel 56 is secured to the upper end of the inner stem 28 thereby providing means for causing manual rotation of the inner stem. It will be understood, however, that a lever or other mechanical device might be substituted for the hand wheel for imparting rotation to the inner stem.

Attached to the sides of the tubular portion 42 of the cap are a pair of studs 58 and 60, pivoted at their lower ends and threaded at their upper ends. Nuts 62 and 64 act to secure a gland follower 66 in position about outer stem 18 to press downwardly against packing 68 in stuffing box 34. By removing the nuts 62 and 64, the gland follower can be raised to a height sufficient to permit packing lower in place and with the gland follower repositioned, the nuts 62 and 64 may then be replaced on studs 58 and 60 and tightened sufficiently to cause the gland to hold the packing under proper pressure in the stuffing box.

Fig. 1 shows the valve in fully closed position. In this position the passageway 10 is at right angles to the port opening 12. The valve seating surface 14 is in intimate contact with the seats 6 and the flow of fluid through the valve is effectively stopped. In this fully closed position, the handle 20 is as shown in full line in Fig. 3. Further clockwise movement of the handle is prevented by its engagement with stop 23 which is attached to yoke 44. The seating surface 14 of the plug valve is forced downwardly and maintained in tight engagement with seats 6 by the application of rotary clockwise movement to hand wheel 56. By turning the wheel to the right, the threads 24 and 26 act to force the valve downwardly since the inner stem 28 is held against vertical movement by the collar 50.

The construction which causes automatic turning and opening of the plug valve 8 as it is moved upwardly from seat 6 to engage the upper valve seat 30 are shown in Figs. 1, 2 and 3. The hollow valve stem 18 has its upper end located within the confines of a helical spring 80, the upper end of which is secured as by welding at 82 to the under side of the yoke collar 46. Inner stem 28 also passes within the spring 80.

The upper end of the hollow valve stem 18 is threaded with a double thread 84 and 86, both threads being of steep pitch and of the square type. These threads at opposite positions are in engagement with lugs 88 and 90 that are affixed to the inside of the lower convolutions of

the spring. The handle 20 is also attached to the valve stem 18 by a key 91 in the manner heretofore explained, and acts in combination with the stops 22 and 23 as means for limiting the rotation of stem 18. As can be seen in Fig. 3, the handle 20 permits stem 18 to rotate through a maximum angle of 90°. When handle 20 is at the left against stop 23, the valve is in closed position. When it is at the right against stop 22, the valve is in open position.

The operation of the foregoing automatic construction is as follows: When the operator desires to open the valve, he will rotate the wheel 56 and stem 28 in a counter-clockwise direction. This will cause valve 8 to be raised from its seats 6, and hollow stem 18 will move further upwardly into the lower end of spring 80. The co-action of the spring carried lugs 88 and 90 with the threads 84 and 86 as the stem 18 moves upwardly will cause the stem 18 and the valve 8 to be rotated in a counter-clockwise direction, which movement, of course, is assisted to some degree by the counterclockwise movement of the threads 24 of the inner stem 28 with respect to the threads 26 in the plug valve. As the raising of valve 8 proceeds, the rotation thereof will continue until it has been turned a full 90°, the engagement of handle 20 with the stop 22 limiting further rotational movement. At this point, the valve will be fully opened, but the upper valve surface 32 will not as yet have come into engagement with the upper valve seat 30. Accordingly, the operator continues rotation of wheel 56 until the seats 30 and 32 are brought into contact. Further upward movement of valve stem 18 to complete the seating of surfaces 30 and 32 is permitted by virtue of the longitudinal compressibility of spring 80. In this way valve 8 can be turned from fully closed to fully open position during the period it is free of engagement with the lower seats 6 or the upper seat 30.

Conversely, when the valve is to be closed, wheel 56 is rotated clockwise, valve 8 is moved downwardly to be freed from seat 30 and then as downward movement continues, the co-action of lugs 88 and 90 with threads 84 and 86 will rotate valve 8 through an arc of 90° clockwise to move it to closed position in which handle 20 will engage stop 23. Thereafter, further downward movement will bring the valve into engagement with the seats 6 to complete the closing operation. Spring 80 may be stretched a trifle when closing is complete.

When the valve is in upper locked position, there will be appreciable clearance between the faces of seats 6 and the seating surface 14 of the plug valve. Since fluids often pass through the valve at high velocities and pressures, the lower end of the plug valve might be caused thereby to vibrate or deflect in an undesirable manner. In order to prevent such vibration or deflection, there is provided at the bottom of the plug valve an extension 70, preferably cylindrical in cross-section and axially aligned with the valve. This extension fits closely within the confines of a socket 72 in the bottom of the valve casing. As the valve is moved up and down, extension 70 correspondingly moves in the socket. Since it is axially aligned with the valve, the extension in no way interferes with the opening or closing operation, but, on the contrary, assists in that it holds the lower end of the valve in correct axial alignment with respect to the valve seats. Should any fluid become trapped in the lower part of socket 72, provision is made for its escape upon the descent of the valve in the form of a small vertical passage 74 which leads into a transverse passage 76 that empties into the open area 16 that surrounds the plug valve.

A modified type of spring element is shown in Fig. 4. Here, instead of using a helical spring such as 80, there is shown a bellows 92, having its upper end fixed to the frame at 94 and with its lower end 96 surrounding the upper end of stem 18. The bellows 92 is in the general form of a doughnut and is compressible and extensible in a lengthwise direction, but has practically no torsional movement under the forces which are applied in the opening and closing of the valve. The thread 84 and 86 on stem 18 and the lugs 88 and 90 on the bellows are the same as those shown in Figs. 1, 2 and 3. If preferred a single thread and single lug only could be used as it is obvious that the number of threads and cooperating lugs is a matter of choice. It is believed apparent that the operation of a valve equipped with a bellows 92 will be the same as that of the valve equipped with spring 80 as shown in Fig. 6.

It is my intention to cover all changes and modifications

of the example of the invention herein chosen for purposes of the disclosure which do not constitute departures from the spirit and scope of the invention.

I claim:

1. A valve comprising a valve body, a passage therethrough, aligned oppositely disposed main valve seats in said passage, a conical plug valve having an opening thereto its position with respect to said valve seats, a tubular outer valve stem extending from said plug valve through an opening in said body, an inner valve stem positioned within said outer valve stem and in threaded engagement therewith, means fixed with respect to said body for maintaining said inner valve stem in fixed vertical position while permitting rotation thereof, a valve seat concentric with said outer stem and surrounding said opening through said plug valve, a corresponding seating surface on said plug valve for closing said opening when said plug valve is in maximum raised position, means for supporting the lower end of said plug valve against lateral displacement regardless of the vertical position of said plug valve, and means for rotating said plug valve comprising a spring element having longitudinal compressibility but negligible torsional movement under the loads to be applied, said element having one end fixed with respect to said valve body and the other end surrounding the upper portion of said valve stem, a thread on the exterior of said valve stem and a thread engaging element connected to said spring element and in engagement with said thread to cause rotation of said stem and plug valve from closed to open position as said plug valve is being raised.

2. A valve comprising a valve body, main valve seats therein to receive a conical plug valve, a conical plug valve having a bore therethrough, a valve stem on said plug valve, a bearing member at the lower end of said plug valve effective to support said lower end regardless of the vertical position of said plug valve, an upper valve seat concentric with said valve stem and above said plug valve, an upper valve surface on said plug valve concentric with said valve stem and adapted to engage said upper valve seat when said plug valve is raised, said upper valve seat and upper valve surface together forming an upper valve, means for raising said plug valve from engagement with said main valve seats to bring said upper valve surface into engagement with said upper valve seat, means for rotating said plug valve while it is disengaged from all said valve seats, said rotating means comprising a spring element having longitudinal compressibility but negligible torsional movement under the loads to be applied, said element having one end fixed with respect to said valve body and the other end surrounding the upper portion of said valve stem, a thread on the exterior of said valve stem and a thread engaging element connected to said spring element and in engagement with said thread to cause rotation of said stem and plug valve from closed to open position as said plug valve is being raised, said upper valve seat and bearing member acting to support said plug valve at both ends when said valve is in maximum raised position and said upper valve seat being located at the only place of egress from the interior of said valve body other than said main valve seats.

3. A valve comprising a valve body, main valve seats therein to receive a conical plug valve, a conical plug valve having a bore therethrough, a valve stem on said plug valve, a bearing member at the lower end of said plug valve effective to support said lower end regardless of the vertical position of said plug valve, an upper valve seat concentric with said valve stem and above said plug valve, an upper valve surface on said plug valve concentric with said valve stem and adapted to engage said upper valve seat when said plug valve is raised, said upper valve seat and upper valve surface together forming an upper valve, means for raising said plug valve from engagement with said main valve seats to bring said upper valve surface into engagement with said upper valve seat, said raising means comprising a threaded member in fixed vertical position with respect to said body and in threaded engagement with an element fixed with respect to said plug valve, means for rotating said plug valve while it is disengaged from all said valve seats, said rotating means comprising a spring element having longitudinal compressibility but negligible torsional movement under the loads to be applied, said element having one end fixed with respect to said valve body and the other end surrounding the upper portion of said valve stem, a thread on the exterior of

said valve stem and a thread engaging element connected to said spring element and in engagement with said thread to cause rotation of said stem and plug valve from closed to open position as said plug valve is being raised, said upper valve seat and bearing member acting to support said plug valve at both ends when said valve is in maximum raised position and said upper valve seat being located at the only place of egress from the interior of said valve body other than said main valve seats.

4. A valve comprising a valve body, main valve seats therein to receive a conical plug valve, a conical plug valve having a bore therethrough, a tubular internally threaded valve stem on said plug valve, a bearing member at the lower end of said plug valve effective to support said lower end regardless of the vertical position of said plug valve, an upper valve seat concentric with said valve stem and above said plug valve, an upper valve surface on said plug valve concentric with said valve stem and adapted to engage said upper valve seat when said plug valve is raised, said upper valve seat and upper valve surface together forming an upper valve, means for raising said plug valve from engagement with said main valve seats to bring said upper valve surface into engagement with said upper valve seat, said raising means comprising an inner stem positioned within said tubular valve stem and in threaded engagement therewith, means for preventing vertical movement of said inner stem with respect to said body, means for rotating said plug valve while it is disengaged from all said valve seats, said rotating means comprising a spring element having longitudinal compressibility but negligible torsional movement under the loads to be applied, said element having one end fixed with respect to said valve body and the other end surrounding the upper portion of said valve stem, a thread on the exterior of said valve stem and a thread engaging element connected to said spring element and in engagement with said thread to cause rotation of said stem and plug valve from closed to open position as said plug valve is being raised, said upper valve seat and bearing member acting to support said plug valve at both ends when said valve is in maximum raised position and said upper valve seat being located at the only place of egress from the interior of said valve body other than said main valve seats.

5. A valve comprising a valve body, a conical plug valve therein and a pair of oppositely disposed corresponding seats, a stem extending from said plug valve through an opening in said body, means for raising said plug valve from seated position, means for rotating said plug valve comprising a spring element having longitudinal compressibility but negligible torsional movement under the loads to be applied, said element having one end fixed with respect to said valve body and the other end surrounding the upper portion of said valve stem, a thread on the exterior of said valve stem and a thread engaging element connected to said spring element and in engagement with said thread to cause rotation of said stem and plug valve from closed to open position as said plug valve is being raised, a valve and valve seat concentric with said stem for sealing the said opening when said plug valve is in maximum raised position, and means for supporting the lower end of said plug valve against lateral displacement regardless of its vertical position.

6. A valve comprising in combination, a casing for connection with piping, a conical plug valve in said casing, a stem fixed to said plug valve and extending through said casing, packing for preventing leakage of fluid from said casing along said valve stem, means for raising said plug valve from seated position, means for rotating said plug valve through a predetermined angle comprising a spring element having longitudinal compressibility but negligible torsional movement under the loads to be applied, said element having one end fixed with respect to said casing and the other end surrounding the upper portion of said valve stem, a thread on the exterior of said valve stem and a thread engaging element connected to said spring element and in engagement with said thread to cause rotation of said stem and plug valve from closed to open position as said plug valve is being raised, means for supporting the lower end of said plug valve when said plug valve is raised from seated position, and means for sealing said stem from the interior of said casing when said plug valve is in maximum raised position whereby said packing may be removed and replaced without loss of fluid while said valve is in operation.

7. A valve comprising in combination, a casing for connection with piping, a conical plug valve in said casing, a stem fixed to said plug valve and extending through said casing, packing for preventing leakage of fluid from said casing along said valve stem, means for raising said plug valve from seated position, said raising means comprising a threaded element vertically fixed with respect to said casing and in threaded engagement with an element fixed with respect to said plug valve, means for rotating said plug through a predetermined angle, said rotating means comprising a spring element having longitudinal compressibility but negligible torsional movement under the loads to be applied, said element having one end fixed with respect to said valve casing and the other end surrounding the upper portion of said valve stem, a thread on the exterior of said valve stem and a thread engaging element connected to said spring element and in engagement with said thread to cause rotation of said stem and plug valve from closed to open position as said plug valve is being raised, means for supporting the lower end of said plug valve when said plug valve is raised from seated position, and means for sealing said stem from the interior of said casing when said plug valve is in maximum raised position whereby said packing may be removed and replaced without loss of fluid while said valve is in operation. 25

8. A valve comprising in combination, a casing for connection with piping, a conical plug valve in said casing, a stem fixed to said plug valve and extending through said

5 casing, packing for preventing leakage of fluid from said casing along said valve stem, means for raising said plug valve from seated position, means for rotating said plug valve through a predetermined angle, said rotating means comprising a spring element having longitudinal compressibility but negligible torsional movement under the loads to be applied, said element having one end fixed with respect to said valve casing and the other end surrounding the upper portion of said valve stem, a thread on the 10 exterior of said valve stem and a thread engaging element connected to said spring element and in engagement with said thread to cause rotation of said stem and plug valve from closed to open position as said plug valve is being raised, means for supporting the lower end of said plug valve when said plug valve is raised from seated position, and means for sealing said stem from the interior of said casing when said plug valve is in maximum raised position whereby said packing may be removed and replaced without loss of fluid while said valve is in operation, said means for sealing said stem comprising a valve seat and a cooperating valve surface on the upper part of 15 said valve. 20
